ELECTRON DISCHARGE DEVICE

Wilfrid F. Niklas, Chicago, Ill., assignor to The Rauland Corporation, a corporation of Illinois

Filed Feb. 16, 1959, Ser. No. 793,431

4 Claims. (Cl. 313—65)

This invention relates to electron discharge devices of the image converter type and more particularly to the object or pickup window of an X-ray image converter envelope.

Conventional image converters are contained in an evacuated envelope, the body of which is substantially cylindrical in shape. One end section of the cylinder is closed and contains provisions for ophthalmic viewing of an image. The opposite end of the cylindrically shaped envelope is closed and customarily includes a spherically shaped object or pickup window area of a material transparent to a particular incident radiation, such as X-rays.

Within the radiation-transparent window area and in close proximity to it, or some instances actually applied on the inner surface of the window area, is a multiple layer pickup screen including a photoemissive cathode. The opposite end of the evacuated enclosure generally contains a fluorescent viewing screen and interposed between the photoemissive cathode and the fluorescent viewing screen is an electron optical system for the purpose of focusing and accelerating an electron image projected from the photoemissive cathode in response to the excitation of incident radiation from a source or object image. It has been noted that the pickup window must be transparent to the incident radiation and in the case of X-ray image converters the window is generally composed of glass. Materials such as aluminum or beryllium may also be used but difficulties of procurement as well as application usually limit their use.

It is essential for the proper operation of an image converter that the sensitivity of the device be as high as possible and that the brightness distribution in the image be as true a reproduction of the X-ray attenuation in the object under observation as it is possible to obtain. Existing image converter devices using an X-ray transparent pickup window of uniform thickness throughout suffer from a deficiency in both of the above elements due principally to the variation in transparency of the uniformly thick radiation-transparent window. Because of the divergent character of X-rays, it can be seen that the X-ray path length through a uniformly thick pickup window, measured at the axis, is substantially less than the X-ray path length through the glass measured at any point which is off the axis and the difference in path length increases with the distance from the axis. This change in path length becomes increasingly pronounced when the pickup window is hemispherical in shape which is the common practice in image converters of the X-ray type.

The transparent window introduces a loss or attenuation to the incident radiation that may be assumed to be constant per unit length in the material and, consequently, with a divergent beam the loss experienced is a maximum at the periphery of the window. The loss in X-ray transmission in the peripheral area of a uniformly thick pickup window in response to a divergent X-ray beam is manifest in an unwanted reduction in brightness in the peripheral area of the reproduced image.

2

It is, therefore, a principal object of this invention to provide a new and improved image converter envelope in which one or more of the aforementioned difficulties encountered with prior art devices are either alleviated or substantially eliminated.

It is another object of the invention to provide an image converter envelope structure having a pickup window in which X-ray transparency is substantially improved.

- 5 10 15 20 25 30 35 40 45 50 55 60
- It is still a further object of the invention to provide an image converter envelope having a structure which permits large image areas to be viewed without suffering a deterioration in sensitivity or undesirable contrast differences.
- An image converter envelope, constructed in accordance with the present invention, comprises a substantially cylindrical section defining a transmission path for an electron image. One end of the cylindrical section is enclosed and contains provisions for viewing an image. The opposite end of the cylindrical section is likewise closed and includes a window area of a radiation-transparent material having a thickness which varies inversely with the distance measured radially from the axis of the cylindrical section and thereby provides a constant transmission path length for incident rays issuing from an external source along the axis of the cylindrically shaped section.

The features of the present invention which are believed to be novel are set forth with particularity in the appended claims. The invention together with further objects and advantages thereof may best be understood, however, with reference to the following description taken in connection with the accompanying drawings in the figures of which like reference numerals identify like elements, and in which:

Figure 1 is a cross-sectional view of an X-ray image converter embodying the invention.

Figure 2 is a schematic view showing the device of Figure 1 partially cut away, together with an external object and X-ray source.

The image converter shown in the drawings comprises an evacuated envelope having a cylindrically shaped central section, a shoulder portion at one end of the cylindrical portion extending radially inwardly toward the axis thereof and including provisions for viewing an image, and a closure portion at the opposite end of the cylindrical section including an X-ray transparent window portion. More specifically, there is an envelope section 10 which, for most of its length, is substantially a cylinder and this section of the envelope is closed at one end by a re-entrant press 11. The aforementioned shoulder portion of the envelope is that which interconnects the cylindrical section with the re-entrant press. The remainder of the glass envelope comprises a substantially spherical glass section 12 having a diameter approximately equal to that of the cylindrical portion of envelope section 10. The sections 10 and 12 are pre-sealed around their perimeters to respective metal flanges 13a and 13b which, in turn, are sealed together by Heliarc welding or the like after the two envelope sections 10 and 12 have been separately processed.

Suitably mounted within envelope section 12 is an electron source in the form of a large diameter multi-layer pickup screen 14 which approximates a sector of a sphere oriented so that its concave surface faces toward the re-entrant end of envelope section 10. The pickup screen, for the specific embodiment under consideration, is sensitive to impinging X-rays and to that end includes an X-ray sensitive phosphor layer such as silver activated zinc sulfide or the like, embedded in a suitable silicon resin 14b and applied to a spherically shaped aluminum support member 14a. Superimposed on the phosphor

layer is the usual barrier layer 14c which may be of aluminum oxide or the like and on the surface of which is applied a photoemissive cathode layer 14d. Photoemissive cathode 14d may be of conventional antimony-cesium composition.

A small diameter fluorescent screen is positioned within the envelope within the area encompassed by the shoulder portion thereof and facing the pickup screen. More specifically, re-entrant section 11 is closed by a flat glass plate 15 having transverse dimensions small with respect to those of the cathode and bearing on its inner face a suitable fluorescent coating to constitute a viewing screen 15a. Silver activated zinc-cadmium sulfide or the like is the fluorescent material generally employed and the screen is preferably aluminized or otherwise provided with a metallic backing layer 15b.

A focusing and accelerating electrode system is interposed intermediate the photoemissive cathode and viewing screen and it comprises a conductive focus electrode 19 adjacent the inner surface of the envelope and an anode 16 encompassing viewing screen 15a. The focus electrode spans substantially the entire cylindrical portion of the envelope and may conveniently take the form of a conductive wall coating having one end terminated at and electrically connected to metal flanges 13a and 13b. The anode 16 is a metallic electrode structure which is partially cylindrical and partially conical in shape terminated at its large end with a skirt portion which may be accommodated by mounting over the re-entrant or returned portion of envelope section 11.

The opposite end of the anode terminates in a substantially spherical shaped cap 17 having an axial and circular aperture 18 which provides access for electrons originating at the photoemissive cathode, admitting such electrons for impingement against viewing screen 15. Like screen 15, the anode also has small transverse dimensions relative to those of the cathode. This, it will be recognized, is usual practice, employing a circular viewing screen having a much smaller diameter than the photocathode in order to obtain a marked intensification of the visible image. The convex face of anode cap 17 faces the concave surface of pickup screen 14. The anode encloses viewing screen 15 and is electrically connected thereto so that the screen is maintained at the same electrical potential as the anode. The structural details of the image converter as thus far described may be entirely conventional and will be familiar to those skilled in the art.

In the operation of the described device, multiple layer pickup screen 14 is operated at or near ground potential through a lead extending through envelope section 12 as indicated at 24. The anode structure connects through a lead 25 to a high voltage source (not shown) which establishes an anode potential of between 25 and 35 kilovolts. Focusing potential is applied to electrode 19 by connection through flanges 13a, 13b and the focus potential is usually in the order of several hundred volts.

Having established the operating potentials, an X-ray image may be admitted through X-ray transparent window section 12 of the envelope to impinge upon pickup screen 14 and excite phosphor layer 14a, as hereinbefore described.

As shown in Figure 2, the X-rays impinging on transparent pickup window 12 are divergent rays from a point source X external of the image converter and in general lying along axis a—a of the tube envelope. Interposed between the X-ray source and X-ray transparent window 12 is object 30 through which the diverging X-rays pass, causing an X-ray image to pass through transparent window 12 and impinge upon pickup screen 14. A conversion is here accomplished in that the X-ray image, by exciting pickup screen 14, causes a corresponding electron image to be developed. This image, in turn, is accelerated along the electron path of the tube to impinge upon screen 15 where a further image conversion takes place, producing a visible image on this screen in the usual way.

In prior art devices transparent window 12 is of uniform thickness throughout and the effective length of the X-ray path through the window increases with increasing radial spacing which results in an undesirable reduction in X-ray transparency which is most pronounced at the peripheral area of the window. The reduction in X-ray transparency with the distance from the axis of the image converter results in a corresponding reduction in X-ray intensity on pickup screen 14 and produces an undesirable brightness variation in the image reproduced on fluorescent screen 15a. In particular, the brightness of this image falls away or decreases in a manner which is essentially the same as the change in effective X-ray transparency of the transparent window due to the effective increase in X-ray path length with radial distance from the tube axis. It can be shown that for a hemispherically shaped pickup window with a radius of 8 inches and an actual uniform window thickness of .080 inch and with a point X-ray source at an axial distance of 24 inches outside the window, the effective thickness of the window increases rapidly to a degree where it may suffer in excess of 20 percent loss of X-ray transmission value within a radial spacing of 5 inches from the axis of the system. It can likewise be shown that similar transmission losses occur across the area of a flat window as occur in the case of a hemispherical window.

The improvements contributed by the present invention center particularly about a preferred form of window 12 which overcomes many deficiencies of prior art structures and imparts to the device under consideration very desirable properties. In accordance with the invention, the thickness of window 12 varies inversely with distance measured radially from axis a—a of cylindrical portion 10 in order to provide a constant transmission path length for any incident rays issuing from an external source X disposed along axis a—a. The thickness of the window varies such that the divergent X-rays originating from source X see equal glass thickness across the entire effective window diameter. Thus the physical thickness of the window decreases with increasing distance from the axis of the window. The preferred window configuration can be expressed by the following geometric function:

$$d_a = d \cos \left[\arctan \left[\frac{r}{L + R \left(1 - \sqrt{1 - \left(\frac{r}{R} \right)^2} \right)} \right] \right] + \arccos \sqrt{1 - \left(\frac{r}{R} \right)^2} \times \sqrt{1 - \left(\frac{r}{R} \right)^2}$$

where

d_a = actual window thickness

d = window thickness at the axis of the tube

R = radius of curvature of outer surface of window

r = radial spacing of the point of incidence for X-rays from the axis of system

L = distance from the X-ray source to outer window surface along axis.

A pickup window constructed in the manner of this invention satisfies the foregoing equation and provides an approximately constant transmission value for all incident X-rays. Thus, the brightness distortion experienced with prior structures, featuring a window of uniform thickness is minimized.

While a particular embodiment of the invention has been shown and described, it is apparent that various changes and modifications may be made, and it is therefore intended in the following claims to cover all such modifications and changes as may fall within the true spirit and scope of this invention.

I claim:

1. An envelope for an image converter comprising: a substantially cylindrical section defining a transmission path for an electron image; an end section affixed to and closing one end of said cylindrical section and having provisions for viewing an image; another end section affixed to and closing the opposite end of said cylindrical section including a window portion of a material which is transparent to invisible radiations, which has the configuration of a sector of a sphere, and which has a thickness varying inversely with distance measured radially from the axis of said cylinder to provide a constant transmission path length for incident rays issuing from an external source disposed on said axis.

2. An envelope for an image converter comprising: a substantially cylindrical section defining a transmission path for an electron image; an end section affixed to and enclosing one end of said cylindrical section and having provisions for viewing an image; another end section affixed to and closing the opposite end of said cylindrical section including a window portion of a material opaque to visible radiation but transparent to invisible radiations, which has the configuration of a sector of a sphere, and which has a thickness varying inversely with distance measured radially from the axis of said cylinder to provide a constant transmission path length for incident rays issuing from an external source disposed on said axis.

3. An envelope for an image converter comprising: a substantially cylindrical section defining a transmission path for an electron image; an end section affixed to and closing one end of said cylindrical section and having provisions for viewing an image; another end section affixed to and closing the opposite end of said cylindrical section including a window portion of glass which is transparent to X-rays, which has the configuration of a sector of a sphere, and which has a thickness varying inversely with distance measured radially from the axis of said cylinder to provide a constant transmission path length for incident rays issuing from an external source disposed on said axis.

4. An envelope for an image converter comprising: a substantially cylindrical section defining a transmission path for an electron image; an end section affixed to and closing one end of said cylindrical section and having provisions for viewing an image; another end section affixed to and closing the opposite end of said cylindrical section including a window portion of a material which is transparent to invisible radiations and which has a thickness varying in accordance with the following function:

10

$$d_a = d \cos \left\{ \arctan \left[\frac{r}{L + R \left(1 - \sqrt{1 - \left(\frac{r}{R} \right)^2} \right)} \right] + \arccos \sqrt{1 - \left(\frac{r}{R} \right)^2} \right\} \times \sqrt{1 - \left(\frac{r}{R} \right)^2}$$

15

20

where

d_a =actual window thickness

d =window thickness at the axis of the tube

R =radius of curvature of outer surface of window

25 r =radial spacing of the point of incidence for X-rays from the axis of system

L =distance from the X-ray source to outer window surface along axis.
